UNITED STATES PATENT OFFICE.

PHILIP H. FARLEY, OF ROCHESTER, NEW YORK.

SHOE-PROTECTING DEVICE.

1,260,888.

Specification of Letters Patent. Patented Mar. 26, 1918.

Application filed October 31, 1917. Serial No. 199,563.

To all whom it may concern:

Be it known that I, PHILIP H. FARLEY, of Rochester, in the county of Monroe and State of New York, have invented certain new and useful Improvements in Shoe-Protecting Devices; and I do hereby declare the following to be a full, clear, and exact description of the same, reference being had to the accompanying drawings, forming 10 a part of this specification, and to the reference characters marked thereon.

The prime object of my invention is to provide a practical device that can be conveniently used for the temporary protection 15 of the upper portions of ladies' shoes, particularly against the soiling and abuse they receive in automobile travel.

In a more specific aspect, the invention is designed to afford an extremely compact, 20 small structure, of light weight, which is cool when worn, and can be carried in the pocket and slipped on and off a shoe in a moment.

A further purpose of the invention is to 25 make a structure which, within certain limitations, will fit shoes of various sizes and shapes, so that it is possible to take care of all sizes of ladies' shoes with two or three standard sizes of the protecting device.

30 An additional object of my improvement is to provide a novel method of constructing and assembling the parts, so as to eliminate the necessity of a lasting or shaping operation, and reduce the manufacturing cost to 35 a minimum figure, placing the device within reach of every automobilist on a basis that makes it economical to thus protect the fine leather of ladies' shoes. To these and other ends the invention consists in certain improvements and combinations of parts, all 40 as will be hereinafter more fully described, the novel features being pointed out in the claims at the end of the specification.

In the drawings:

45 Figure 1 is a plan view of my invention; Fig. 2 is a perspective view;

Fig. 3 is a transverse sectional view on line 3^a—3^a of Fig. 1, and

Fig. 4 is a detail view of the upper blank.

50 Similar reference characters throughout the several views indicate the same parts.

Ladies' fine shoes and slippers are greatly soiled and damaged from traveling, even short distances in vehicles such as 55 mobiles, owing to the usual amount of grease and dirt which quickly accumulates, and the

customary low position of a person sitting in a motor vehicle, which has a tendency to bring the toe portion of the upper into contact with the dash board and sides of the 60 vehicle body. To overcome this, I have constructed the present device which can be slipped on a shoe in a moment and adequately protects the forward or toe portion of the shoe upper, while at the same 65 time it is of such a light construction as not to discommode the wearer, or to increase the heat of the foot appreciably.

The device comprises a bottom or sole portion 1, of one thickness, which is of less 70 extent than the sole of the shoe, so as to extend over only the forward part thereof. Attached to the bottom portion 1 is the upper 2 which is preferably shorter at its central part than the bottom portion, and 75 extends over only the forward or toe portion of the shoe upper. The upper 2 is made from a thin, light skin, or other suitable light weight material with sufficient strength and flexibility for the purpose contemplated. 80 The device is held in place by an elastic band 3, the ends of which are attached to the under side of the upper 2 at its rear edge, while the band can be readily slipped over the heel portion of a shoe and holds the 85 protector in position. The upper is attached to the bottom portion in such a manner as to obviate any lasting or shaping it, while at the same time providing for adequately fitting shoes of different sizes in an efficient 90 and comfortable manner, and I will now describe the method by which this is accomplished.

The upper blank, which is shown in Fig. 95 4, is curved at its former end to conform generally to the shape of the bottom or sole portion, although it is somewhat wider at such forward portion, and is provided with a series of V-shaped notches 4, preferably three in number. The adjacent edges 4^a of 100 these notches are then superimposed upon each other with the outside surfaces of the leather or other material of which the upper is formed engaging each other, and are thus stitched together. This operation reduces the width of the toe portion of the upper until it is approximately the size of the toe portion of the bottom or sole, and also provides three seams with the free edges disposed interiorly of the upper. These 105 110 seams cause the upper to stand up at the toe portion, forming a vertical wall as shown at

4^b, and giving an enlarged interior space of sufficient extent and of a proper shape to readily incase various sizes and shapes of shoe toes. The lining 5, which is cemented 5 or otherwise secured to the inner surface of the upper 2, is cut away at its forward end on the line 6, leaving the interior seams on the upper free and exposed. The lining serves to stiffen and support the rear part 10 of the upper 2, holding it properly shaped, and permits the seamed portion at the forward end to maintain the desired vertical relation with the remaining part. 7 designates a lining or covering extending over 15 the bottom or sole portion and cemented or otherwise secured thereto.

The upper, with the lining attached, is then superimposed on and stitched to the bottom or sole portion 1, the stitches 20 extending through the respective edge portions which overlie each other and extend in the same direction. This method of stitching, as well as the seamed portion at the front, make it possible to construct the device 25 vice without any lasting or shaping operation, the interior form being such as to fit evenly, over the toe portion of a shoe of a generally similar style or shape, even though the shoe be smaller or somewhat differently 30 shaped from the protecting device.

The structure can be manufactured at a relatively low cost, and constitutes an exceedingly practical device for the purpose intended, while at the same time possessing 35 an extremely neat and pleasing appearance.

I claim as my invention:

1. A shoe protecting device comprising a bottom portion of less length than the sole of a shoe and adapted to extend over only 40 the forward part of the sole, and an upper adapted to extend over only the toe portion of the shoe upper and having its outer edge superposed on and extending in the same

direction as the edge of the bottom portion to which it is stitched along their adjacent edges, said upper portion having a series of seams at the toe extending upwardly from the bottom portion and formed by adjacent inwardly projecting edge portions of the upper which are stitched together along said edge portions. 45 50

2. A shoe protecting device comprising a bottom portion of less length than the sole of a shoe and adapted to extend over only the forward part of the sole, an upper adapted 55 to extend over only the toe portion of the shoe upper and having its outer edge superposed on and extending in the same direction as the edge of the bottom portion to which it is stitched along their adjacent 60 edges, said upper portion having a series of seams at the toe extending upwardly from the bottom portion and formed by adjacent inwardly projecting edge portions of the upper which are stitched together along said 65 edge portions, and a lining which is substantially coextensive with the upper except at the toe portion where it is cut away around said seams.

3. The method of making a shoe protecting device which consists in cutting a series of V-shaped notches at the edge of the toe portion of an upper blank and superposing the outside surfaces adjacent to each notch upon each other and stitching them together, 75 thereby forming a series of seams on the inside of the upper, securing to the inside of the upper a lining which is cut away at the forward portion of the upper to expose the seamed portion, and stitching the upper 80 and lining to a bottom portion with the edges superposed on and extending in the same direction as the edges of the bottom portion. 70 75

PHILIP H. FARLEY.
